[57] CLAIM

The ornamental design for a current probe, as shown and described.

DESCRIPTION

FIG. 1 is a top, front, and right side perspective view of a current probe showing my new design, with the cord member being eliminated for ease of illustration; FIG. 2 is a top plan view of the device.

FIG. 3 is an elevational view of the device, as seen from the right side of FIG. 1, the device having been rotated 180° about its longest axis. The view of the other side of the device is a mirror image.

FIG. 4 is a bottom plan view;

FIG. 5 is a front elevational view; and

FIG. 6 is a rear elevational view thereof.
